Filed Dec. 17, 1965, Ser. No. 232

Term of patent 14 years

(Cl. D58—2)

FIG. 1.

FIG. 5.

FIG. 3.

FIG. 2.

FIG. 4.

FIG. 6.

FIG. 1 is a perspective view of a flexible dispensing container, showing our new design.

FIG. 2 is a side elevational view thereof showing the side opposite that shown in FIG. 1.

FIG. 3 is an end elevational view thereof, taken from the left of FIG. 2.

FIG. 4 is an end elevational view thereof, taken from the right of FIG. 2.

FIG. 5 is a top plan view thereof.

FIG. 6 is a bottom plan view thereof.

The characteristic feature of our design resides in the presence, on a flexible dispensing container having the configuration shown, of a representation of a handle on the upper surface of each face of the container opposite the higher end containing the means for forming a pouring lip, all as shown.

We claim:

The ornamental design for a flexible dispensing container, as shown and described.
